[57] CLAIM

The ornamental design for a throat protecting attachment for a baseball catcher's mask, as shown and described.

DESCRIPTION

FIG. 1 is a front elevational view of a throat protecting attachment for a baseball catcher's mask, showing my new design, the attaching straps being shown in unfolded, extended position;

FIG. 2 is a rear elevational view;

FIG. 3 is a side elevational view, the opposite side being a mirror image thereof;

FIG. 4 is a bottom plan view thereof; and,

FIG. 5 is a top plan view thereof.

FIG-4

FIG-5
